(74) Attorney, Agent, or Firm — FisherBroyles, LLP;
Craig W. Mueller**CLAIM**

The ornamental design for a knife, as shown and described.

DESCRIPTION

FIG. 1 is a perspective view of the knife;
FIG. 2 is a front elevation view thereof;
FIG. 3 is a rear elevation view thereof;
FIG. 4 is a top plan view thereof;
FIG. 5 is a bottom plan view thereof;
FIG. 6 is a left elevation view thereof;
FIG. 7 is a right elevation view thereof; and,
FIG. 8 is a perspective view thereof, wherein a removable
blade has been removed from a blade carrier.
The broken lines are directed to portions of the knife that
form no part of the claim.
